US0D1030703S

(12) **United States Design Patent** (10) **Patent No.:** **US D1,030,703 S**
(45) **Date of Patent:** **** Jun. 11, 2024**

(54) **WIRELESS HEADPHONES**

(71) Applicant: **New Audio LLC**, New York, NY (US)

(72) Inventors: **Thomas C. Wilson**, Brooklyn, NY (US); **Clayton J. Pipkin**, Highland Park, NJ (US); **Marten Wallby**, Malmo (SE); **Zachary Hellman**, New York, NY (US); **Jonathan Levine**, New York, NY (US)

(73) Assignee: **New Audio LLC**, New York, NY (US)

(**) Term: **15 Years**

(21) Appl. No.: **29/910,816**

(22) Filed: **Aug. 24, 2023**

Related U.S. Application Data

(62) Division of application No. 29/796,516, filed on Jun. 24, 2021, now Pat. No. Des. 1,000,416.

CLAIM

The ornamental design for wireless headphones, as shown and described.

DESCRIPTION

FIG. 1 is a perspective view of wireless headphones showing our new design, viewed from the top and front.

FIG. 2 is a top plan view thereof.

FIG. 3 is a bottom plan view thereof.

FIG. 4 is a front profile view thereof.

FIG. 5 is a back profile view thereof.

FIG. 6 is a first side profile view thereof; and,
FIG. 7 is a second side profile view thereof.

The broken lines depict portions of the wireless headphones that form no part of the claimed designs.

1 Claim, 7 Drawing Sheets
